Primary Examiner — Vy N Koenig(74) *Attorney, Agent, or Firm* — Quarles and Brady LLP(57) **CLAIM**

The ornamental design for a box, as shown and described.

DESCRIPTION

FIG. 1 is a perspective view of a box showing my new design, when closed;

FIG. 2 is a top plan view thereof;

FIG. 3 is a first elevational view thereof;

FIG. 4 is a second elevational view thereof;

FIG. 5 is a third elevational view thereof;

FIG. 6 is a fourth elevational view thereof;

FIG. 7 is bottom plan view thereof;

FIG. 8 is a perspective view of the box when opened;

FIG. 9 is a top plan view thereof;

FIG. 10 is a first elevational view thereof;

FIG. 11 is a second elevational view thereof;

FIG. 12 is a third elevational view thereof;

FIG. 13 is a fourth elevational view thereof; and,

FIG. 14 is a bottom plan view thereof.

The broken lines shown in the drawings depict features of the box that form no part of the claimed design.
